UNITED STATES PATENT OFFICE.

GEORGE M. MARSH, OF EAST RANDOLPH, NEW YORK.

FOLDING IRONING-BOARD.

1,196,130.

Specification of Letters Patent. Patented Aug. 29, 1916.

Application filed July 14, 1916. Serial No. 109,347.

To all whom it may concern:

Be it known that I, GEORGE M. MARSH, a citizen of the United States, residing at East Randolph, in the county of Cattaraugus and State of New York, have invented a new and useful Folding Ironing-Board, of which the following is a specification.

The device forming the subject matter of this application is a means for housing and 10 operating an ironing board.

The invention aims to provide novel means whereby when a closure for a cabinet which contains the ironing board is manipulated, the ironing board may be disposed in 15 an operative working position, and be held securely in such position.

It is within the province of the disclosure to improve generally and to enhance the utility of devices of that type to which 20 the present invention appertains.

With the above and other objects in view which will appear as the description proceeds, the invention resides in the combination and arrangement of parts and in the 25 details of construction hereinafter described and claimed, it being understood that changes in the precise embodiment of the invention herein disclosed can be made within the scope of what is claimed, without 30 departing from the spirit of the invention.

In the accompanying drawings: Figure 1 shows in side elevation, a device constructed in accordance with the present invention, the ironing board being lowered into a working 35 position; and parts of the supporting structure appearing in section; Fig. 2 is a vertical longitudinal section of the structure forming the subject matter of this application, the ironing board being disposed 40 within the cabinet; and Fig. 3 is a fragmental front elevation wherein the ironing board is shown lowered, as in Fig. 1.

In the accompanying drawing, the numeral 1 indicates a support which may be a 45 wall. A floor appears at 2.

In carrying out the present invention there is provided a box-like cabinet 3 which is open at the front, the cabinet 3 being attached to the wall 1 in any suitable manner. 50 The cabinet 3 comprises side walls 4, a top 5 and a bottom 6. A vertically swinging closure 7 for the cabinet 3 is provided. The closure 7 includes a lower panel 8 and an upper panel 9. The lower end of the upper 55 panel 9 is secured to the upper end of the lower panel 8 by means of one or more

hinges 10. Hinges 11 unite the lower end of the lower panel 8 with the bottom 6 of the cabinet 3. Secured to the lower panel 8 are spacing blocks 12. Secured to the spacing blocks 12 is an ironing board 14. The outer end 15 of the ironing board 14 projects beyond the outer or upper end of the lower panel 8, and is spaced from the inner face of the upper panel 9. A leg 16 is 60 united by means of a hinge 17 with the projecting end 15 of the ironing board 14. A flexible element 18 forms a connection between the leg 16 and the upper panel 9. Hooks 19 are pivoted to the side edges of 65 the upper panel 9. The lower panel 8 is provided at its edges with projections 20. There are projections 21 on the outer faces of the side walls 4 of the cabinet 3.

When the ironing board 14 is held within 75 the cabinet 3, as shown in Fig. 2, the cooperation between the various parts of the structure is as follows:—The lower panel 8 and the upper panel 9 are alined vertically, and form a closure for the open front of 80 the cabinet 3, the hooks 19 on the upper panel 9 being engaged with the projections 21 on the side walls 4 of the cabinet 3, so that the closure cannot swing downwardly. The leg 16 stands in an upwardly projecting 85 position between the end 15 of the ironing board 14 and the upper panel 9, the flexible element 18 hanging in a loop between the leg 16 and the panel 9.

When it is desired to dispose the ironing 90 board 14 in the horizontal, working position of Fig. 1, the operation is as follows:—The hooks 19 on the upper panel 9 are detached from projections 21 on the side walls 4 of the cabinet 3. The lower panel 9 is 95 then swung downwardly on the hinges 10 until it overlaps the outer face of the lower panel 8. By this operation, the flexible element 18 is tightened up and the leg 16 is pulled outwardly, until it stands at right 100 angles to the board 14, which is still in a vertical position within the cabinet 3. When the flexible element 18 is tightened up as aforesaid, the leg 16 is brought into abutment with the upper end of the lower 105 panel 8 and with the corresponding end of the upper panel 9. The lower panel 8 is now swung downwardly on the hinges 11 until the parts appear as shown in Fig. 1, the hooks 19 having previously been 110 engaged with the projections 20 on the edges of the lower panel 8, so as to hold the panel

9 underneath the panel 8, as shown in Fig. 1. Since the panel 9 is held in the position shown in Fig. 1, the flexible element 18 is kept taut, thereby preventing the leg 16 from swinging in the direction of the arrow A in Fig. 1, and because the leg 16 abuts against the ends of the panels 8 and 9, as clearly shown in Fig. 1, the leg cannot swing in the direction of the arrow B.

10 Having thus described the invention, what is claimed is:—

1. In a device of the class described, a cabinet; a vertically swinging closure for the cabinet, the closure comprising a lower panel hinged at its lower end to the lower end of the cabinet, and an upper panel hinged at its lower end to the upper end of the lower panel; an ironing board secured to the inner face of the lower panel and including a projecting end spaced from the upper panel; a leg located in the space between said end of the board and the upper panel and hinged at its lower end to the board; and a flexible connection between the upper end of the leg and the upper end of the upper panel.

2. In a device of the class described, a cabinet; a vertically swinging closure for the cabinet, the closure comprising a lower panel hinged at its lower end to the lower end of the cabinet, and an upper panel hinged at its lower end to the upper end of the lower panel; an ironing board secured to the inner face of the lower panel and including a projecting end spaced from the upper panel; a leg located in the space between said end of the board and the upper end of the panel and hinged at its lower end to the board; a flexible connection between the upper end of the leg and the upper end of the upper panel; the outer end of one panel forming an abutment for the leg when the board and both panels are low-

ered and when the upper panel is swung beneath the lower panel; and means for detachably connecting the panels when the upper panel is swung beneath the lower panel, thereby to tighten the connection and to hold the leg in abutment with the outer end of the abutment-forming panel.

3. In a device of the class described, a cabinet; a vertically swinging closure for the cabinet, the closure comprising a lower panel hinged at its lower end to the lower end of the cabinet, and an upper panel hinged at its lower end to the upper end of the lower panel; an ironing board secured to the inner face of the lower panel and including a projecting end spaced from the upper panel; a leg located in the space between said end of the board and the upper panel and hinged at its lower end to the board; the panels and the board being adapted to be lowered, and the upper panel being adapted to be swung beneath the lower panel, and the leg being adapted to be disposed in a depending position to form a support for both panels; and a detachable connection including a part on the lower panel, a part on the upper panel, and a part on the cabinet, the part on the upper panel being adapted to engage with the part on the lower panel when the upper panel is folded beneath the lower panel, and the part on the upper panel being adapted to engage the part on the cabinet when the panels are vertically aligned to form a closure for the cabinet.

In testimony that I claim the foregoing as my own, I have hereto affixed my signature in the presence of two witnesses.

GEORGE M. MARSH.
